UNITED STATES PATENT OFFICE.

PATRICK B. DELANY, OF NEW YORK, N. Y.

SYNCHRONOUS TELEGRAPHY.

SPECIFICATION forming part of Letters Patent No. 440,767, dated November 18, 1890.

Application filed July 30, 1886. Serial No. 209,557. (No model.)

To all whom it may concern:

Be it known that I, PATRICK B. DELANY, a citizen of the United States, and a resident of the city, county, and State of New York, 5 have invented certain new and useful Improvements in Multiple Telegraphy, of which the following is a specification.

In various Letters Patent of the United States heretofore granted to me I have shown 10 systems of synchronous telegraphy based upon the idea of splitting up or subdividing a main line into a number of independent circuits by means of synchronously-moving circuit-completers traversing over a circle of 15 insulated segments at each end of the main line in such manner that all the sub-circuits can be simultaneously operated in either direction. In working such synchronous systems it has been considered necessary that the 20 traveling circuit-completers rest at the same time upon corresponding segments—in other words, that the circuit-completers must at the same time rest on segments connected in the same sub-circuit and the line must be such 25 that a current sent into it at one end can reach and manifest itself at the other end during the time the circuit-completers remain in contact with said segments. Such an operation is suitable for short lines, and has the 30 advantage that the pairs of operators on any sub-circuit can communicate in either direction at all times; but the system cannot be practically operated under the conditions above recited where the line is of such length 35 or where, by reason of cables, underground wires, or other causes of increased resistance of the main line, the "time" or retardation of the line is such that with segments of reasonable practicable size, such as I have heretofore generally used, an impulse sent into one 40 segment at one end of the line cannot reach and manifest itself on the segment belonging to the same sub-circuit at the other end of the line during the time that the circuit-completers are upon said pair of segments. This 45 difficulty might be overcome by increasing the widths of the segments proportionally to the time of the line; but that would greatly decrease the transmitting or message capacity 50 of the line and be objectionable for other reasons, or other ways might be devised. For

instance, in a pending application filed by me I have shown an organization for the purpose in which the feature of reciprocal communication over each sub-circuit is retained. 55 In operating the synchronous systems to which I refer it has therefore always been a necessary condition that the circuit-completers rest simultaneously upon contacts with which the terminal instruments of a given 60 sub-line are connected. The rotating circuit-completers must therefore be synchronous as regards their contact with the segments with which any given sub-circuit is connected, though they need not necessarily be synchronous 65 as regards actual correspondence of position relatively to the points of the compass on the circles of segments.

My present invention is in part based upon the idea of transmitting impulses or messages 70 over the line and sub-circuits in one direction only and of receiving the impulses in their proper successive order upon segments which allow for the time of the line irrespective of the position or synchronism of the circuit-completers. In other words, provided the circuit-completers run isochronously or make given revolutions in the same period of time, it is immaterial whether the circuit-completers are synchronous in either the sense of always 75 occupying exactly corresponding positions with reference to the circle of segments or synchronous in the sense of resting at the same moment upon segments connected in the same sub-circuit. For instance, in my 80 present method of working herein described, if the circuit-completers are run synchronously in either of the senses above mentioned, the operation would be as follows: If both circuit-completers rested at the same moment 85 upon segments, each numbered 1 and occupying exactly corresponding positions, a transmitted impulse sent into the line would not be received upon the other segment No. 1, but would be caught upon that segment which 90 was properly located according to the time of the line. Thus if the time of the line was equal to one segment the impulse would be manifested on segment No. 2, and if the time was equal to two segments the impulse would 95 be received on segment No. 3. Again, if the circuit-completers are not synchronous as re-

gards correspondence of position—that is, if, for instance, at the transmitting end the circuit-completer rests on No. 1 segment at the moment the receiving circuit-completer rests 5 on No. 4 segment—the transmitted impulse would in like manner be received upon that segment located beyond No. 4 in such position according to the time of the line as to properly catch the impulse. From what has already been said it will doubtless have been 10 perceived that an impulse sent into the line through a segment having a given number may be received upon the segment having a like number, one circuit-completer being run 15 ahead of the other. To restate the matter briefly, the transmitting-operators may all be working and a succession of impulses be sent into the line at one end as the circuit-completer traverses the segments, and at the receiving end of the line such successive impulses will in exact and proper rotation be received upon segments located so as to allow 20 for the time of the particular line and irrespective of the numbers they bear.

25 The invention also contemplates certain improvements in the construction and operation of apparatus more particularly adapted to the practice of the method of operation above recited than the apparatus now in use.

30 In the accompanying drawings, Figure 1 is a view in elevation of an improved arrangement of the motor and distributor or rotating circuit-completer. Fig. 2 is a diagram view illustrating circles of segments which may be 35 used in connection with such apparatus, and also illustrating improved arrangements for maintaining the proper movement of the circuit-completers at both ends of the main line. Figs. 3 and 4 are diagram views illustrating 40 portions of circles of segments at connected stations, and Fig. 5 is a similar view.

For convenience of description I will first 45 describe the apparatus shown in Figs. 1 and 2. A is the rotating toothed armature-wheel, and B the motor-magnet, which may be energized by a suitable arrangement of electric 50 circuits, contacts, and vibrator, such as shown in my various patents. On the spindle of the armature-wheel is arranged a toothed 55 wheel C, which gears with a pinion C' on a counter-spindle D, arranged centrally within the circle of segments E and carrying a trailing finger or circuit-completer d'. If the pinion C' has one-twelfth the number of teeth 60 that the toothed wheel C has, it will be rotated twelve times during one revolution of the wheel C, and the segments in the circle may be reduced to one-twelfth the number that would otherwise be desirable. Of course 65 these relative proportions are mentioned merely by way of example, and any suitable and desirable relation of the parts may be adopted.

In my prior patents the armature-disk A is 70 described as being rotated about three times per second. If in the arrangement described the disk should be driven at the same rate,

the circuit-completer would be rotated about thirty-six times per second.

I do not wish to limit myself to the special 70 mechanism shown and above described, as the principle of operation is obviously not in any way dependent upon particular details of construction.

In my Patent No. 286,278 I have shown and 75 described each operator as having twelve segments taken at equal intervals in the circle of segments. With the present arrangement it will be obvious that each operator would only require one segment in order to get the same 80 number of connections with the main line.

The message-segments are numbered from 1 to 12, and, as viewed in the drawings, those numbered alike occupy corresponding positions in the two circles. The intermediate 85 segments z are used for separating the message-segments, and also when desired for grounding the line. They are separate and independent of each other and of the other segments, and may individually be connected 90 in any desired way to ground or otherwise.

By giving an increased speed of rotation to the circuit-completer and reducing the number of insulating-segments, as above described, various advantages result—as, for instance, the grouping of a number of segments into one circuit is unnecessary; the segments may be made larger than heretofore; the segments being reduced in number the instruments can be made more cheaply; bad effects 95 from inequalities in the circle of segments are avoided; there is no unevenness in the continuity or regularity of the impulses on each circuit, as is somewhat the case with the old plan on account of the arrangement of the 100 correcting-segments; the circle of segments may be made smaller, thus reducing friction to a minimum, and the apparatus is specially 105 adapted for working according to my improved method above referred to.

One arrangement for effecting the synchronous correction of this apparatus is illustrated in diagram in Fig. 2, which shows the correction sending and receiving segments and their connections with the battery and 115 correcting devices and the way in which the latter act on the vibrator or reed.

It has been deemed unnecessary to illustrate the manner in which the vibrator controls the motor-circuit, as that may be done 120 in exactly the same way described in a large number of patents heretofore granted to me.

The correcting-impulses are all sent from one end of the line from X to Y, as illustrated in the figure, and may be either accelerating or retarding impulses, according to the position of the circuit-completer at the receiving-station. One correcting-impulse for each revolution of the circuit-completers will be ample, as the speed of rotation is comparatively high. At station X three large 125 segments similar to the message-segments are shown as devoted to the correction of the speed of the apparatus. The correcting-bat-

terry C B is shown as connected with the first one of these segments, and the other two may be grounded. More than three segments could be used, if desired, or only two might 5 be used, and the segments might be reduced in size or connected differently, according to the requirements of any special circuit. At station Y the space corresponding to that occupied by the three correcting-segments at 10 station X is occupied by a number of smaller segments—say seven—(marked *a b c d e f g*,) which may be the same size and preferably have segments *z' z* arranged at each side of the group.

15 In the arrangement shown in Figs. 2, 3, and 4 provision is made for the time or retardation of the line, and the correction-receiving segments are displaced relatively to the battery-connected correction-sending segment at station X. The middle one *d* of the smaller segments is shown as grounded. Such segment is displaced according to the amount of retardation of the line—that is, if the circuit-completers are running in the same relation to the corresponding segments the current sent in at the battery-segment at station X will be delivered into the segment *d* at station Y. If the circuit-completer at Y, however, is tardy and rests upon the segment *a* 20 at the moment the current manifests itself, a correcting-impulse of acceleration will be imparted to the apparatus at station Y in a manner presently described, and if the circuit-completer rests upon the segment *g* a 25 correcting-impulse of retardation will be given the apparatus at Y, as presently described. The segments *z'* and *z* are preferably normally grounded, so as to keep the line free from any current as the circuit-completer 30 comes upon the correcting-segments and as the circuit-completer leaves such contacts to come upon the first message-segment. The other smaller segments may also be grounded, as shown, if desired, to discharge the correcting-battery current from the line when the 35 apparatus is running properly, and other segments than those mentioned may be connected for correction, according to the retardation of the line. The vibrator V, in this 40 instance a reed being shown, is actuated by its local circuit and battery B, as is well understood. A resistance R is included in the local circuit and is normally shunted out of the circuit through the wire *r* and armature 45 *R'* of a magnet *R*, which is included in a normally-closed local circuit *s*, which runs through the armature *S'* of a magnet *S*, through the coil of which an accelerating-contact *a* is connected to earth.

50 As explained in my prior patents, a decrease of the electro-magnetic power of the vibrator-circuit will cause an acceleration of the vibrator. If, therefore, the circuit-completer at Y should be tardy and the transmitted correcting-impulse should manifest itself upon the segment *a*, the magnet *S* would be energized, its armature attracted, the local 55

broken, and the shunt *r* opened by the armature *R'* leaving its front stop. This would throw the resistance *R* into the vibrator-circuit and cause a momentary acceleration of the vibrator.

70 The retarding-contact *g* is connected through the coil of a magnet *O* to earth. The armature of this magnet normally rests against its back stop, thus closing a local circuit *O'*, in which the coil of a magnet *P* is included. The normal attraction of the armature of the magnet *P* against its front stop closes a shunt *P'* around a battery *P*² in a local circuit *Q*, 75 which includes the coils of a double magnet *Q'*, the poles of which are arranged on opposite sides of the end of the reed and are provided with adjustable screw pole-pieces, as fully described in my prior patents. If, therefore, the circuit-completer rests upon the retarding-contact *g* when the correcting-impulse transmitted from X manifests itself, the armature of the magnet *O* will be attracted, the local *O'* opened, and the shunt *P'* 80 broken, thus causing the local battery *P*² to become effective in the coils of the magnet *Q'*, creating a magnetic field around the end of the reed and producing a retardation of its vibration, as described in my prior patents.

85 Other methods than those illustrated of controlling the vibrator at station Y may of course be used.

90 Having now described one form of my improved apparatus for carrying out my method, one way of arranging the correcting-contacts, and one way of making the corrections, either for acceleration or retardation, effective, I will now refer again particularly to the correction of the apparatus and then to the method of transmitting messages.

95 From what has been said it will have been perceived that it is entirely immaterial what point in the circle is selected for the location of the correcting-segments. In other words, 100 as it is entirely immaterial whether the circuit-completers run synchronously as regards actual position or synchronously as regards resting upon exactly corresponding segments at the same time, the correction-receiving 105 segments may be selected at any point in the circle. When both circuit-completers are running properly, the current sent in from the correcting-battery C B at the distant station will be delivered into the ground located between the accelerating and retarding 110 segments. If the receiving circuit-completer is running out of time, then when the transmitted correcting-impulse has reached the circuit-completer and the circuit-completer 115 touches the accelerating or retarding-contact 120 the speed of the receiving apparatus will be 125 increased or diminished.

130 In Fig. 3 I have shown two connected stations with a portion of a circle of segments at each station. In these circles the segments are the same size, whether they be for correction or messages, while the interposed ground-segments *z* are somewhat smaller. I

might, however, make all the segments the same size and connect them for use in any manner desired.

Referring to Fig. 3, if I select segment 5 marked O at station X for connection to the correcting-battery C B, I may select at the other station Y any segments desired. For instance, I may select Nos. 2 and 4 for connection to the accelerating and retarding apparatus, as indicated. In that event I would ground at the receiving-station segment No. 3, and also, preferably, the separating or ground segment on each side of it. This would give a ground-contact between the accelerating and retarding segments of considerably greater area than that of the segment O from which the correcting-impulse was sent into the line. A similar arrangement is exhibited in Fig. 2. This is a desirable feature, because the current will discharge at Y more slowly than it comes in at X, and by providing this enlarged area of ground-contact the line will be properly discharged between the correcting-segments 2 4 and not affect the retarding apparatus when the circuit-completer runs upon segment 4. I might connect a segment on the outside of the accelerating or retarding segment to the accelerating or retarding devices to catch all the correcting-current, if desired, 30 thus providing an area of contact for the delivery of a correcting-impulse to the correcting devices larger than the segment from which the impulse was sent into the line, or I might connect the correcting-battery with 35 two segments and the retarding or accelerating devices each with three segments, as shown in Fig. 4. In this figure the segments are all the same size. They may be connected as desired. At station X, Fig. 3, I might, as 40 shown, ground the separating or ground segment and the adjoining main segment on each side of the segment O with which the correcting-battery C B is connected. This, however, is not necessary, and under some conditions by leaving these segments open a more marked effect will be produced at Y by the 45 transmitted impulse.

Now, in regard to the transmission of messages, such transmission should, in order to 50 utilize the full capacity of the line, be in the same direction that the correcting-impulses are sent over the line; in other words, transmission should be from X to Y, as shown in the drawings. Operators' sending-instruments S may, therefore, be connected with each 55 of the message-segments at X, and receiving-instruments R may be connected with each of the receiving message-segments at Y. If the time of the line is equal to the space between 60 two message-segments, then a message sent on segment 6, for instance, would be received at Y on segment 7. If the time of the line is equal to two message-segments, then it would be received on segment 8. It will therefore 65 be readily perceived that if all the operators connected with the message-segments at X should transmit simultaneously the trans-

mitted impulses would be successively sent into the line, and the receiving-segments at Y being properly selected according to the 70 time of the line such message-impulses would in proper and accurate succession be delivered through the proper segments to the receivers, and this irrespective of the position of the circuit-completers, provided they make 75 a revolution in the same period of time.

As above remarked, the correcting-segments or message-segments may all be made the same size and connected as desired. For instance, very small segments insulated from 80 each other, but arranged closely together, could be used and two or more such segments connected together so as practically electrically to form a single segment either for correction or transmission of messages. In Fig. 85 4 I have shown the message-segments all the same size, and in both Figs. 3 and 4 have illustrated the use of several segments connected together so as to electrically constitute one segment; but obviously, so far as this part 90 of my invention is concerned, the condition and operation will be precisely the same if the segments were made very much smaller, and a suitable number connected together to give the required area of contact. 95

I have above spoken of receiving a correcting-impulse upon a greater area of contact than the segment from which the impulse was sent into the line—in other words, of providing for the spread or slower discharge 100 of the received current. The same principle might be adopted with reference to the message-segments, and each receiving-operator might have two receiving-segments and the current only be sent into the line at the other 105 end on one segment. In that event the idle segment at the transmitting-station could be either grounded or left in the air, as desired. Such an arrangement is seen in Fig. 4, where S' at X indicates a key and battery connected 110 to one contact, the adjoining contact being grounded. At Y the corresponding receiver R' is connected with both contacts. 115

In an apparatus like that illustrated in Fig. 3 it might be considered desirable, and probably would be under some circumstances, to have the correcting-segments smaller than the others—say one-half the size—so they could be connected independently in any manner desired, as suggested in connection with the 120 description of Fig. 2 or otherwise. Instead of controlling the circuit-completers by corrections of acceleration and retardation, the receiving apparatus might be run faster or slower than the other apparatus and be controlled by corrections of opposite tendency. 125

In the figures thus far described the trailers are shown as running together—i. e., in the same relation to the correspondingly marked or numbered segments. An objection to working according to this plan is that one or more of the message-segments to the left of the correcting-segments (as viewed in the drawings) must be idle, because if a mes- 130

sage-current were sent into such a segment it would be delivered into some one or more of the correcting-segments at the receiving end of the line, and thus prevent the proper 5 running of the apparatus. At the beginning of this specification it is stated that one circuit-completer may be run ahead of the other. Such an arrangement is shown in Fig. 5, and has certain advantages over those above described. In that figure the segments are shown as of same size. They may of course be made of any desired size and connected to accomplish the desired results, as fully stated above in connection with the other figures. As before, two stations X and Y are shown. The 15 correcting-segments at both stations are marked *a b c d e f*. At the correction-sending station X a segment *c* is connected with the correcting-battery, the segments *a b* on the left and *d e* on the right being grounded. At station Y segment *c* is grounded, *b* connected with acceleration devices, *d* with retardation devices, and *a* and *e* are grounded. Segment *f* may be left in the air or grounded; or, if 25 it is desired to have two segments connected to the correcting-battery and two to the corresponding ground at Y, the segment *f* may be utilized. As shown, the trailer at X is running ahead of that at Y, the difference between them depending on the time of the 30 line. Thus, assuming the time of the line to be three segments, while the trailer at X is on correcting-battery segment *c* trailer at Y is on the segment ahead of *a*; but by the 35 time the latter trailer reaches *c* the current from the correcting-battery has arrived and is discharged into the ground. The relative positions are clearly shown by the full and dotted lines. If trailer at Y is tardy, the current from C B will be delivered into the accelerating devices connected with *b*, and if 40 too fast into the retarding devices connected with *d*. Of course the message-currents are transmitted in the same way—that is to say, 45 an impulse sent into the line at X through any message-segment would arrive at Y by the time the trailer there had reached the corresponding segment and would be delivered through said segment to the receiving-instrument corresponding with the transmitter from which the impulse was sent. With this 50 plan there is no idle space in the circles, because the received current, either for messages or correction, is delivered into segments corresponding with those from which the current is sent out. It will also be noted that the trailers automatically adjust themselves to the time of the line, for when they 55 are started to rotating the trailer at Y will be accelerated or retarded until it finds its true relation to the trailer at X and delivers the current from C B into the ground through segment *c*. Changes in the condition of the 60 circuit affecting its time, arising from atmospheric or other causes, are automatically compensated, because if a change tending to reduce the time of the line occurs the current

from C B will reach the trailer at Y while it is still upon segment *b*, and the trailer will be accelerated and the distance between the 70 two trailers correspondingly reduced. A corresponding retarding effect is produced by the retarding devices if the time of the line should increase. The instruments, therefore, are adapted to any lines, and no special 75 adoption or change is required to work them on any circuit.

In starting the apparatus both trailers are caused to rotate at what is approximately the same speed, and, if necessary, the speed of 80 trailer at Y may be slightly adjusted until the correcting-impulses are delivered into the ground *c*.

The advantages of my improved method of working besides those above mentioned are 85 that a great number of circuits may be worked over any given line, and the received impulses will be strong and effective, because all the current arriving at the receiving-station is delivered into the receiving-segment 90 and not partly into adjoining ground-segments, as is the case when operating in both directions under my patented system.

Obviously the apparatus hereinbefore described may on sufficiently short lines be operated according to the plans set forth in my 95 patents already granted.

The special apparatus above described is not essential to the practice of my improved method of working, though I deem it specially 100 well adapted for the purpose. The apparatus shown in my prior patents might with little, if any, change be worked according to my present plan, though there would be certain objections to it. 105

Two main lines could be used advantageously—one for sending, the other for receiving—and the operators' instruments arranged in relation to each other similar to the common disposition of quadruplex lines, so that 110 the operator receiving on No. 1 circuit of one wire may break the operator on No. 1 circuit of the other wire. This is a common arrangement in quadruplex telegraphy and needs no illustration. 115

No claim is made herein to the broad idea of sending an impulse from one segment and receiving it on another so displaced relatively to the sending-segment as to allow for the time or retardation of the line, as such 120 subject-matter is claimed in another pending application filed by me.

No claim is made herein to the method of operation, as that is claimed in a divisional application filed by me. 125

I claim—

1. The combination of the several segments for correction, messages, and grounding, said segments being arranged in a circle independently insulated and provided with independent binding posts or contacts, so that they may be independently connected, as desired. 130

2. The combination of the insulated message-segments, the insulated correction-seg-

ments, and the independently-insulated interposed ground-segments having each an independent binding-post, whereby they are capable of being connected independently to 5 ground or otherwise, as desired.

3. The combination of the electrically-driven disk, its spindle, the counter-spindle, gearing interposed between the spindles, the trailer, and the circle of segments.

10 4. The combination of the primary driven spindle, a second spindle, interposed mechanism by which the latter spindle is driven at an increased speed, the trailer carried by the latter spindle, and the circle of segments.

15 5. The combination of the line, circles of segments, rapidly-rotating trailers traversing them and connected with the line, the speed of rotation of said trailers being so related to the segments that each operator need be connected with but one segment in each circle

20 for multiplex Morse transmission, correction-sending segments located at one point only in one circle of segments, and correction-receiving segments located at one point only in 25 the other circle of segments.

6. The combination of a main line, a circle of insulated segments, electrically - driven traversing circuit-completer and its controlling -vibrator or circuit-interrupter at each 30 end of the line, a correcting-battery connected with a segment at one end of the line, at the other end of the line a segment connected with circuit-completer accelerating devices, and also a segment connected with circuit- 35 completer retarding devices, and a ground-connected contact arranged between said accelerating and retarding segments, said ground-contact having an area not less than the area of the segment or contact through 40 which the correcting-current is sent into the line at the distant station.

7. The combination of a main line, a circle of insulated segments, electrically - driven traversing circuit-completer and its controlling-vibrator or circuit-interrupter at each 45 end of the line, a correcting - battery connected with a segment at one end of the line, at the other end of the line a segment connected with circuit - completer accelerating 50 devices, and also a segment connected with circuit-completer retarding devices, the segments of both of said devices having an area

of contact not less than the segment through which the correcting-impulse is sent into the line at the distant station, and a ground-connected contact arranged between said accelerating and retarding segments. 55

8. The combination of a main line, a circle of segments, electrically - driven traversing circuit-completer and its controlling-vibrator 60 or circuit-interrupter at each end of the line, a correcting-battery connected with a segment at one end of the line, and at the opposite end of the line correcting-segments located in a group at one point only in the circle, one of 65 said segments corresponding with the distant battery-connected segment being connected to ground, another of said segments on one side of said grounded segment connected to accelerating devices, and another of said segments on the other side connected to retarding devices, substantially as set forth. 70

9. The combination of a main line, a circle of segments, electrically - driven traversing circuit-completer and its controlling-vibrator 75 or circuit-interrupter at each end of the line, a group of correcting-segments in one of the circles of segments, a correcting-battery connected with the middle segment of said group, connections between the other segments of 80 said group and the earth, a corresponding group of correcting-segments in the other circle, a connection between the ground and the middle segment of the latter group, vibrator-accelerating devices connected with the segment or segments on one side of the middle grounded segment, and vibrator-retarding devices connected with the segment or segments on the other side of said middle segment. 85

10. The combination of the circles of contacts and trailers at each end of the line, a battery and transmitting devices connected with a contact in one circle for sending impulses over the line, and corresponding receiving devices at the distant end of the line 95 having a relatively greater contact area in the circle for the reception of said impulses, for the purpose set forth. 90

In testimony whereof I have hereunto subscribed my name.

PATRICK B. DELANY.
